UNITED STATES PATENT OFFICE.

GROVER CLEVELAND WHITEFORD, OF WILMINGTON, DELAWARE.

RECEPTACLE FOR MAIL-BAGS.

No. 874,878.

Specification of Letters Patent.

Patented Dec. 17, 1907.

Application filed October 3, 1907. Serial No. 395,805.

To all whom it may concern:

Be it known that I, GROVER CLEVELAND WHITEFORD, a citizen of the United States, residing at Wilmington, county of New Castle, State of Delaware, have invented a new and useful Receptacle for Mail-Bags, of which the following is a specification.

My invention relates to a new and useful mail bag receiver and consists in providing means for receiving the bag from a train and directing same to a suitable point.

It further consists of other novel features of construction, all as will be hereinafter fully set forth.

Figure 1 represents a vertical sectional view of a mail bag receiver embodying my invention. Fig. 2 represents an end elevation thereof.

Similar numerals of reference indicate corresponding parts in the figures.

Referring to the drawings. My invention is designed to receive a mail bag or pouch from a moving train and to conduct same to a suitable point without danger or injury to the bag or contents thereof and in the drawings I have shown a construction for carrying out my invention but it will be evident that other instrumentalities may be employed and various changes may be made in the construction which will come within the scope of my invention and I therefor desire to make such changes as may be necessary.

1 designates the casing of the receptacle which is formed of any suitable material and is preferably of substantially horse-shoe shape, the mouth 2 thereof being of sufficient size to receive a mail bag and the cross section of the receptacle gradually decreasing in size to a suitable point, as in the present instance at 3, after which the casing remains the same size. The lower wall of the mouth 2 is curved downwardly as at 4 while the side walls thereof are curved as at 5.

6 designates a bar having a curved lower wall 7 and which is secured to the casing in any suitable manner in the present instance by rivets 8, said bar having a shoulder 9 which projects slightly in front of a rod 10, which is pivotally supported by the casing 1 and carries the door 11, it being understood that the bar 6 and curved lower wall 7 thereof prevents the bag from coming in contact with the rod 10.

12 designates a weight which is suitably connected with the door and serves to nor-

mally hold the same in its closed position, as seen in Fig. 1.

13 designates a stop forming part of or connected with the lower wall of the casing and against which the door 11 is adapted to rest 60 when in normal position.

14 designates a spring arm which is suitably secured to the casing and which is normally in such position as to receive the impact of the mail bag after it has passed the 65 door 11, as will be evident.

It will be noted that I preferably make the receptacle 5 with the lower portion thereof embedded in the ground and I provide a post 15 which is preferably secured to the casing 1 70 at the rear thereof in the present instance by bolts 16.

17 designates a door which is hinged to the casing and closes the lower opening or exit end thereof, it being understood that said 75 door may be provided with a suitable locking mechanism, whereby it can only be opened by the proper party.

18 designates posts which are suitably supported and to which is secured the bar 19 80 which passes beneath the upper arm of the receptacle and serves as a support therefor. I of course provide a suitable space in front of the door 17 for access to the same.

The operation of the device will be apparent. The receptacle is placed at a suitable point adjacent the railway track with the flaring mouth facing in the direction in which the train approaches. The bag can be carried by any suitable support on the car such 90 as by a string or any other device and as the train passes the receptacle the pouch is directed into the mouth 2, the flaring walls 5 and 4 of which positively insure the proper positioning of the bag with respect to the 95 mouth, while the inclined walls 7 of the bar 6 serve not only to assist in directing the bag properly against the door 11 but will prevent the same from coming in contact with the rod 10 and thus injure the contents of the 100 bag. When the bag strikes the door 11 it overcomes the weight 12 and the door 11 will be swung in the direction indicated by the arrow in Fig. 1, so that the bag will pass into the receptacle and will be thrown against the 105 spring 14 which will give sufficiently to prevent injury to the bag or its contents but at the same time stops the too rapid passage thereof, so that the bag will pass down to the lower portion of the receptacle and will re-

110

main there to be removed by the proper party from the door 17 when it is desired. It will be seen that in this way I provide a receptacle which is positive in its action and will not injure the bag or its contents and in which the mail bag can remain with perfect safety until the removal thereof and at the same time by reason of the position of the door and its immediate closing after the passage of the bag, rain, water, etc., cannot enter the receptacle. The receptacle will be positively supported by the means described although any suitable form of support may be employed.

15 It will, of course, be evident that the door can be pivoted at the bottom instead of at the top of the receptacle and the weight placed in the proper position therefor, in which event the door would swing downwardly in place of upwardly as shown in the drawings, the weight returning to its closed position.

20 Having thus described my invention, what I claim as new and desire to secure by Letters Patent,

1. In a device of the character described, a receptacle having a suitable opening for the reception of a mail bag, a closure for said opening adapted to be opened by the mail bag, means for normally holding said closure in a closed position and said receptacle gradually decreasing in size from said opening to a suitable point.
2. In a device of the character described, a receptacle having a suitable opening for the reception of a mail bag, a closure for said opening adapted to be opened by the mail bag, means for normally holding said closure in a closed position said receptacle having a 35 discharge opening, and a door controlling said discharge opening.

- 35
- 40

3. In a device of the character described, a receptacle having a suitable opening for the reception of a mail bag, the walls of said receptacle being flared at said opening, a 45 weighted door controlling said opening and a spring carried within said receptacle and between which and the walls of the latter the mail bag is adapted to pass whereby the movement of the bag is retarded.

4. In a device of the character described, a receptacle having an opening for receiving a mail bag, the walls of said opening being flared, a rod pivotally mounted in said receptacle and carrying a door, a bar having a 55 curved outer face adapted to be seated in front of said door for preventing the mail bag from coming in contact therewith, a spring on the interior of said receptacle between which and the walls of the latter the mail bag 60 is adapted to pass whereby the movement of the bag is retarded.

5. In a device of the character described, a receptacle having an opening for the reception of a mail bag, a door for said opening, 65 means for normally holding said door closed, and means for limiting the movement of said door.

6. In a device of the character described, a receptacle having an opening for the reception of a mail bag, the walls of said opening being curved outwardly at said opening, a door for said opening, means for normally holding said door closed, and for returning the same to a closed position, and resilient 70 means on the interior of said receptacle against which the mail bag is adapted to strike after passing said door.
